No. 670,497.

Patented Mar. 26, 1901.

H. HILL.

CIRCULAR WARP MACHINE.

(Application filed Sept. 22, 1900.)

(No Model.)

Fig. 2.

UNITED STATES PATENT OFFICE.

HENRY HILL, OF NOTTINGHAM, ENGLAND.

CIRCULAR-WARP MACHINE.

SPECIFICATION forming part of Letters Patent No. 670,497, dated March 26, 1901.

Application filed September 22, 1900. Serial No. 30,825. (No model.)

To all whom it may concern:

Be it known that I, HENRY HILL, a subject of the Queen of England, residing at Nottingham, England, have invented certain new and useful Improvements in Circular-Warp Machines, (for which application has been made in Great Britain under No. 4,584, dated March 10, 1900,) of which the following is a specification.

10 This invention relates to improvements in circular-warp machines for producing seamless tubular-warp lace fabrics.

The invention will be best understood by reference to the accompanying drawings, in 15 which—

Figure 1 is an elevation showing the right half in section; and Fig. 2, a plan, partly in section, of a circular-warp machine constructed according to my invention.

20 Like letters indicate like parts throughout the drawings.

According to my invention the needles A are arranged radially in a plane approximately at right angles to the axis of the machine, with their hooked ends toward the said axis, as shown.

The shank or outer end of each needle A is secured to a needle-jack B, and the latter are mounted in radial recesses C', formed in the 30 upper face of an annular slay-ring C. This slay-ring C is mounted in an annular recess in the upper face of the circular bed D, which is formed with an axial opening D'. The inner ends of the needles A also work in gates 35 or recesses formed in the upper end of a sleeve E, which is secured in the axial opening D' in the bed D, and through the interior of which sleeve the fabric is carried as it is produced.

40 The cam-ring F for operating the needle-jacks is placed in an annular recess formed in the under side of the slay-ring C, with its upper face level with the bottom of the recesses C'. This cam-ring is provided with a 45 number of cam-grooves F' in its upper face (see Fig. 2) equal in number to the number of needle-jacks employed, said grooves F' being tangential to a circle of less diameter than the cam-ring F, as shown.

50 Each needle-jack B is provided with a nib or projection B', (see Fig. 1,) and each of the latter engages in a separate and distinct cam-

groove F' in the cam-ring F, so that by reciprocating the latter the whole of the needles are moved radially inward or outward simultaneously.

Instead of attaching the needles A to needle-jacks B, I may, if desirable, employ what are known as "cranked" needles; but I prefer the arrangement described, as it gives greater strength.

The cam-ring F is reciprocated by means of an eccentric G or other suitable device on the vertical shaft H, which latter is carried in bearings H' H', secured to or formed integrally with the bed-plate D. The rod G' of the eccentric G is connected to the cam-ring F by means of a short arm I, the outer end of which is connected by a pin or axle I' to the end of the said rod, while the inner end 65 passes through openings D³ (see Fig. 1) formed in the bed D and slay-ring C and is secured to the cam-ring F.

The needle-jacks B are held in the slay-ring F by a cover J, which may be rotatable 75 and also formed with a removable section, which latter may be rotating the cover be moved over any point of the slay-ring in order to permit of the removal of any of the needle-jacks.

80 The thread-guides K, (see Fig. 1,) which are arranged in two equal sets, upper and lower, are arranged radially in the space in the center of and concentrically with the needles, and they are carried and operated by 85 the following arrangement: The shanks of the upper set are secured in the enlarged lower end of a sleeve L, which latter is mounted in a bearing L' on a bracket L², secured to the bed D. The shanks of the lower set are 90 mounted in the enlarged lower end of a sleeve M, which is mounted within the sleeve L. Both sleeves L and M are raised and lowered simultaneously by a forked lever N, pivoted at N' to the bracket L². The forked ends N² 95 of this lever are provided with pins N³, which engage with slots N⁴ in the sleeves L M. The end N⁵ (see Fig. 1) of the lever N is actuated by a cam or other suitable device on the vertical shaft H, which is not shown.

100 At the upper end of each of the sleeves L and M is an arm O, provided with a pin O'. These pins engage with the inner slotted ends of two levers P and P', which are pivoted to

the bracket L². The outer ends of these levers engage, respectively, with cams Q Q', which are mounted on a vertical pivot R on the bracket L². These cams are attached to 5 a toothed wheel S, which engages with a pinion S' on the shaft H. One cam, Q', operates the sleeve L and the other, Q, the sleeve M. They are thus each moved angularly independently of each other a distance and in a 10 direction which is determined by the formation of the respective cams, which latter are shaped according to the mesh it is desired to produce.

The threads T (see Fig. 1) are carried on a 15 beam or roller placed above the machine and may be carried through holes in a rib T' on the bearing L'. The fabric as it is produced is carried downward through the axial opening in the sleeve E to take-up rollers, if preferred, of any well-known form, which are placed immediately below the bed.

What I claim as my invention, and desire to secure by Letters Patent, is—

1. In a circular-warp machine, the combination with the needles arranged radially 25 with their hooks toward the axis of the machine, of means for supporting them, a cam provided with tangential cam-grooves for moving the whole of them simultaneously, 30 thread-guides which are arranged radially within the circle of the needles, and means for moving the same both parallel to the axis of the machine and also angularly substantially as described.

2. In a circular-warp machine, the combination with the needles of a slay-ring to support them, a cam-ring provided with tangential cam-grooves for operating them, and means for reciprocating the same, substantially as described.

3. In a circular-warp machine, the combination with the needles of a slay-ring to sup-

port them, a cam-ring provided with tangential cam-grooves for operating them, a bed for supporting the slay and cam rings, and means 45 for reciprocating the cam-rings, substantially as described.

4. In a circular-warp machine, the combination with the thread-guides, of two sleeves, one working within the other for carrying and 50 operating the same, a bearing in which the outer sleeve is mounted, means for raising and lowering the sleeves, and means for moving them angularly one independently of the other substantially as described.

5. In a circular-warp machine, the combination with the needles, of needle-jacks for carrying them, a slay for supporting the needle-jacks, a cam-ring provided with tangential cam-grooves for operating them, means 60 for reciprocating the same, the thread-guides, two sleeves one working within the other for carrying and operating the latter, a bearing in which the outer sleeve is mounted, means for raising and lowering the sleeves, and 65 means for moving them angularly, substantially as described.

6. In a circular-warp machine, the combination with the needles arranged radially with their hooks toward the axis of the machine, means for moving said needles radially 70 thread-guides arranged radially within the circle of the needles, and means for moving them parallel with the axis of the machine and angularly thereto; substantially as de- 75 scribed.

In testimony whereof I have signed my name to this specification in the presence of two subscribing witnesses.

HENRY HILL.
